UNITED STATES PATENT OFFICE

136,253

DESIGN FOR AN EMBOSSED LEATHER

Leonard I Friedman, New York, N. Y.

Application July 10, 1943, Serial No. 110,643

Term of patent 7 years

To all whom it may concern:

Be it known that I, Leonard I Friedman, a citizen of the United States of America, residing in New York city, county of New York and State of New York, have invented a new, original, and ornamental Design for an Embossed Leather, of which the following is a specification, reference being had to the accompanying drawing, forming a part thereof.

The figure on the drawing is a plan view of an embossed leather showing my new design.

I claim:

The ornamental design for an embossed leather, substantially as shown.

LEONARD I FRIEDMAN.
